[57] CLAIM

The ornamental design for an airplane swing, as shown and described.

DESCRIPTION

FIG. 1 is a perspective view of an airplane swing, showing my new design;

FIG. 2 is a top plan view thereof;

FIG. 3 is a front elevation view thereof;

FIG. 4 is a rear elevation view thereof;

FIG. 5 is a left side elevation view thereof; and

FIG. 6 is a bottom plan view thereof.

For convenience of illustration, FIGS. 2 through 6 are shown with the upper portion omitted.
